UNITED STATES PATENT OFFICE.

CHARLES PLACE, OF CAMBRIDGE, MASSACHUSETTS.

DESIGN FOR A JEWELRY AND PIN CUSHION.

SPECIFICATION forming part of Design No. 16,778, dated July 6, 1886.

Application filed May 26, 1886. Serial No. 203,330. Term of patent 3½ years.

To all whom it may concern:

Be it known that I, CHARLES PLACE, a subject of the Queen of Great Britain, residing at Cambridge, in the county of Middlesex and 5 Commonwealth of Massachusetts, have invented and produced a new and original Design for Jewel and Pin Cushions, of which the following is a specification, reference being had to the accompanying drawing, forming a 10 part thereof.

The accompanying drawing represents a view in side elevation of my newly-designed jewel and pin cushion or display-card with pins or jewelry displayed thereon.

15 The base or pedestal A is of the shape or configuration of the hull of a boat or yacht; and the structural frame above the said base consists of the slightly-raking support B and the nearly-horizontal bars C and D, representing, respectively, the mast, boom, and bow-sprit of a yacht attached to the said base, as shown.

20 In the angle formed by the intersection of the bars B and C is the cushion E, having the 25 contour of and representing a mainsail and a gaff-topsail, the line of the gaff being marked

by the ornamental cord x, and said cushion being provided with ornamental bands at the points l, m, n, o, g, and y.

In the angle formed by the intersection of 30 the bar B and the line of the bar D extended are the three cushions F, G, and H, representing, respectively, a stay-sail, a jib, and a flying jib, and being provided with ornamental bands at the points i, j, k, u, v, and o, 35 and the ornamental cords g s and o f.

I claim—

The design for a jewel and pin cushion herein shown and described, the same consisting of the outline of the spars and sails of a boat 40 or yacht provided with ornamental cords and bands, as set forth, and standing above the conventional outline of a hull in elevation.

In testimony whereof I have signed my name to this specification, in presence of two 45 sub-scribing witnesses, on this 24th day of May, A. D. 1886.

CHARLES PLACE.

Witnesses:

JOHN WOODBURY,
MICHAEL MAGINNIS.
